(57) **CLAIM**

The ornamental design for a console for construction machine as shown and described.

DESCRIPTION

FIG. 1 is a perspective view of a console for construction machine showing my new design;

FIG. 2 is a partially enlarged perspective view thereof;

FIG. 3 is a front view thereof;

FIG. 4 is a left side view thereof;

FIG. 5 is a right side view thereof;

FIG. 6 is a top view thereof;

FIG. 7 is an enlarged cross-sectional view of portion A taken along line 7-7 in FIG. 3 thereof; and,

FIG. 8 is a partially enlarged front view thereof.

The dash-dash broken lines depict portions of the console for construction machine, the dot-dash broken lines define the bounds of the claimed design; all broken lines form no part of the claimed design.
